J. H. WOODBERRY

FUSE

Filed Oct. 22, 1919

Inventor
John H. Woodberry

UNITED STATES PATENT OFFICE.

JOHN H. WOODBERRY, OF WASHINGTON, DISTRICT OF COLUMBIA.

FUSE.

Application filed October 22, 1919. Serial No. 332,564.

(FILED UNDER THE ACT OF MARCH 3, 1883, 22 STAT. L., 625.)

To all whom it may concern:

Be it known that I, JOHN H. WOODBERRY, a citizen of the United States, stationed at Washington, District of Columbia, have invented an Improvement in Fuses, of which the following is a specification.

The invention described herein may be used by the Government, or any of its officers or employes in prosecution of work for the Government, or by any other person in the United States, without payment of any royalty thereon.

The particular object of this invention is to provide a construction of fuse in which the firing-pin-driving spring is compressible upon impact of the projectile carrying the fuse.

The accompanying drawing discloses an exemplary embodiment of the underlying principles of the invention. Briefly described:—

Figure 1 is a view in longitudinal axial section of a fuse embodying my improvements, showing the normal position of the parts thereof;

Figure 2 is a similar view, showing the position the parts assume upon impact;

Figure 3 is a fragmentary detail view, in side elevation, of the firing-pin carrier or housing.

Referring, now, in detail to the drawing:—

My invention is shown applied to the type of fuse (shown in my copending application filed September 20, 1919, Ser. No. 325,277) embodying a longitudinally movable plunger 1, carrying, at opposite ends thereof, a primer 2 and a detonator 3. The plunger is normally maintained in safety or unarmed position by suitable means, such as spring-pressed locking-bolts 4, which are centrifugally movable to release the plunger in a manner well known in the art. Upon impact, the plunger, by its inertia, moves toward the firing-pin.

5. designates a tubular firing-pin housing carrying a head 6, and provided with diametrically oppositely disposed, longitudinally extending slots 7, 7, having lateral off-set portions, or curved terminals, 12, for a purpose presently appearing.

Movable in said housing 5 is a firing-pin, comprising, in this instance, a shank or stem 8, a pointed extremity 9, and a circumferential enlargement 10. Extending diametrically through the circumferential en-

largement is a peg 11 projecting at both ends thereof beyond the circumferential. Obviously, however, the circumferential enlargement and peg may be integral, that is to say, the circumferential enlargement may be provided with integral projections corresponding to the projecting ends of the peg 11. The projecting ends of the peg 11 are disposed in the slots 7, 7 and, at the limit of movement of the firing-pin in one direction, are adapted to enter lateral off-set portions, or curved terminals, 12 of the slots 7, 7. Encircling the shank 8 of the firing-pin is a coiled driving-spring 13 bearing against the collar 10 at one end, and at its other end against an interior annular wall 14 in a screw closure 15 provided with an axial recess 16 for the reception of the stem or shank 8 of the firing-pin when the latter moves in the direction thereof.

The normal position of the parts is as shown in Fig. 1, in which the firing-pin spring is uncompressed, and enlargement 10 bears against head 6.

In operation, upon impact of the projectile carrying the fuse, the plunger 1 moves toward the firing-pin. Simultaneously, the firing-pin by its inertia, moves forward, thereby compressing the spring 13. In such movement, the projecting ends of the peg 11, move in the slots 7, 7 until they reach the off-set portions or curved terminals 12, 12 whereupon the firing-pin twists, so that the projecting ends of the peg enter said off-set portions.

So long as the resistance is such as to cause the inertia of the firing-pin to produce a force greater than and counter to the force of the spring 13, the firing-pin spring remains compressed. When the resistance becomes insufficient to keep the firing-pin spring compressed, the spring extends itself with a force equal to the difference between the force due to the inertia of these parts and the force of the spring. If the cessation is sufficiently sudden, the firing pin will be projected into the primer with sufficient force to explode the same. If, however, the resistance should cease gradually, the firing-pin spring would also extend gradually, and, consequently, the firing pin, moving thus slowly under the influence of the slowly-expanding spring, will not have sufficient force to fire the primer. To obviate such occurrence, means are provided for retarding the extension of the

spring until sufficient force is stored therein to fire the primer when the spring extends. This retardation of action of the spring is accomplished by cutting the inclined walls 5 17 of the curved terminals 12, in which the projecting ends of the peg 11 rest, at such an angle to the slots 7, 7 that it will require a force sufficiently great to fire the primer to overcome friction between the peg ends 10 and said curved walls 17 and drive the projecting ends of the peg into the longitudinal slots 7, 7. It will thus be seen that a gradual cessation of resistance to penetration will not cause the spring 13 to extend gradually, but with sufficient force, 15 in all cases, to fire the primer. The projecting ends of the peg 11 rotate out of the branches or curved terminals 12, 12 and then, with a longitudinal movement, the 20 firing-pin is propelled, under the action of its driving spring, against the primer.

It will thus be seen that the fuse gives an automatic selective delay in firing, through mechanical means, the delay, in all cases, being proportional to the resistance encountered. 25

Having described my invention, what I claim as new and desire to secure by Letters Patent, is:—

A fuse embodying, firing elements normally held spaced apart from each other and movable upon impact in the same direction, one of said elements carrying a detonator normally remote from the main explosive charge and moved upon impact to 30 a position adjacent said charge, means energized by movement of the other element on impact for impelling said element toward its normal position after impact, and means for delaying the action of said impelling means. 35

JOHN H. WOODBERRY. 40
